ORNAMENTAL TRIMMING IN THE FORM OF
HEADS AND TAILS OF ANIMALS SUIT-
ABLE FOR POCKETBOOKS

Joseph Rubenstein, Brooklyn, N. Y.

Application May 13, 1938, Serial No. 207,797

8 Claims. (Cl. 41—34)

This invention relates to new and useful improvements in a head and tail ornament for pocketbooks.

More specifically, the invention proposes the construction of a pocketbook characterized by a pair of hingedly connected frame sections for engagement on the mouth opening of a pocketbook and having a means for releasably supporting head and tail ornaments upon the side portions thereof.

Another object of this invention is to form the frame sections of channel shaped material in cross sections and to form the head and tail ornaments with studs which are adapted to be engaged through aligned bayonet openings formed in the side portion of the frame sections, and a strip which is slidably supported within the side portion of the frame section and which is adapted to be moved to a position in which it will clamp the headed studs in position between the bayonet slots for holding the head and tail ornaments in position.

Another object of this invention is to form a pocketbook which has the head and tail ornaments securely attached to the sides thereof.

Still further it is proposed to construct a pocketbook which has an ornament associated with the mouth opening and which is securely attached thereto for ornamental purposes only.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a pocketbook having head and tail ornaments constructed according to this invention.

Fig. 2 is a side elevational view of the frame per se.

Fig. 3 is an enlarged sectional view on the line 3—3 of Fig. 2.

Fig. 4 is an enlarged sectional view of a portion of Fig. 2.

Fig. 5 is a sectional view on the line 5—5 of Fig. 4.

Fig. 6 is an enlarged sectional view of still another part of Fig. 2.

Fig. 7 is an enlarged sectional view on the line 7—7 of Fig. 6.

Fig. 8 is a sectional view on the line 8—8 of Fig. 1.

Fig. 9 is a view looking in the direction of the line 9—9 of Fig. 1.

Fig. 10 is a children's pocket bag constructed according to a modification of the invention.

Fig. 11 is a sectional view on the line 11—11 of Fig. 10.

Fig. 12 is a side elevational view of a children's bag constructed according to a still further modification.

Fig. 13 is a sectional view on the line 13—13 of Fig. 12.

Fig. 14 is a fragmentary enlarged view looking in the direction of the line 14—14 of Fig. 12.

Fig. 15 is a perspective view, illustrating another modified form of the invention.

The heads and tails ornament for ladies' or children's pocketbooks or bags, according to this invention, comprises a pair of hingedly connected frame sections 10 for engagement on the mouth opening of a pocket bag 11. Each frame section 10 has side portions 10^a of channel shape in cross section with the arms thereof adapted to be clamped upon the edges 11^a of the pocketbook proper. A strip 12 is slidably mounted in each side portion 10^a and has a projecting portion 12^a by which it may be moved. An ornamental body 13 for the outer side of the side portion has headed studs 14 which are adapted to engage through aligned bayonet openings formed in the strip 12 and the side portion 10^a. A means is provided for holding this strip in positions in which the bayonet slots are in or out of line for holding and releasing the headed studs.

The frame sections 10 are constructed of metal or other suitable material and the bottom ends 35 of the side portions 10^a are hingedly connected together at a point 15. The pocketbook proper is constructed of leather or similar material and has its edges 11^a around the mouth opening securely clamped between the edges of the channel shaped frame sections and those portions of the bag 11 which are clamped between the arms of the channel members are securely attached together by means of stitches.

The top portions 10^b of the frame sections 10 are each provided with locking elements 16 which are adapted to be engaged with each other for holding the pocketbook closed. The side of the pocketbook 11 is formed with a handle 17 which has its ends 17^a securely attached to the side of the pocketbook by means of stitches 18.

The ornamental bodies 13 consist of a head 13^a for one side of the pocketbook, and a tail ornament 13^b for the other side of the pocketbook. These ornaments 13 are securely attached at their 55

inner ends to members 19 which are formed with the headed studs 14.

The intermediate portion of the channel shaped material from which the frame sections 10 are formed have bayonet openings 20 having their larger ends 20^a directed toward the top of the pocketbook and through which the enlarged head of the studs 14 are adapted to be passed. The strips 12 are slidably passed through slots 21 formed in a portion of the frame sections 10 and are adapted to extend downward within the side portions of the frame sections. These strips 12 are also formed with bayonet openings 22 which have their enlarged ends 22^a opposed to the enlarged openings of the bayonet openings 20 and which are adapted to be aligned with the enlarged openings 20^a so that the enlarged heads of the stud 14 may be passed through these bayonet openings.

20 A pin 23 extends from the inner wall of the frame sections 10 and is adapted to engage an elongated slot 24 formed in the strip 12 for assisting the slot 21 and the side arms of the side portions 10^a in holding the strip in position within the channel shaped material from which the frame sections are constructed.

The intermediate portion of the channel shaped material from which the frame sections are formed have recesses 25 in the vicinity of the lower end of the strip 12 and which are adapted to be selectively engaged by a projection 26 formed on the bottom end of the strip 12 for holding the strip in one or the other position and comprises the means for holding the bayonet slots in or out of line for holding and releasing the headed studs 14. Thus when the strip 12 is moved to the dot and dash position 12' shown in Fig. 6 the enlarged ends 20^a and 22^a of the bayonet opening 20 and 22 will be aligned so that the enlarged heads of the studs 14 may be passed therethrough for disengaging the ornaments 13 from the frame sections 10.

When the strip 12 is moved to the position illustrated by the full lines in Fig. 6 the enlarged ends 20^a and 22^a of the bayonet openings will be out of line so that the narrow portions of these slots will engage the shank portion of the studs 14 and be disposed between the enlarged head and intermediate portion of the side portion 10^a for fixedly holding the ornaments in position thereon. With this construction a person may have the ornaments 13 in position upon the side portions of the pocket bag 11 for adding to the decorative value thereof, or may remove them, as desired.

According to the modification shown in Figs. 10 and 11 a pocketbook 20 constructed of leather or suitable materials is adapted to be closed by a flap 20^a attached to one side of the mouth opening of the pocketbook and which is formed with a snap fastener 21 which is adapted to engage a complementary snap fastener on the adjacent face of the pocketbook proper. This bag is also formed with hingedly connected frame sections 22 which are engaged across the mouth openings of the pocketbook and a handle 23 having its ends 23^a attached to the sides of the mouth opening of the bag for carrying the same.

Ornaments 24 in the form of a head 24^a at one side of the bag and a tail 24^b at the other side of the bag, have their inner ends inserted between the adjacent edges of the bag 20 and securely attached thereto by means of stitches 25. These ornaments 24 are formed from substantially the same material as the pocket bag proper and are

stamped with the desired ornaments, such as eyes, mouth, ears, and the hair which forms the tail 24^b. Stuffing 26 is inserted between the adjacent layers of the ornaments 24.

According to the modifications shown in Figs. 12-14 inclusive, a pocketbook 30 having side walls 30^a is formed with a handle 31 which has its ends 31^a securely attached to one of the side walls 30^a by means of stitches 32. Ornaments 33 are attached to the edge portions of the mouth opening of the bag 30 for adding to the decorative effect of the bag.

These ornaments 33 are in the form of fish or other objects and are formed along their length with slots 34. The upper ends 30^{aa} of the side walls 30^a are adapted to be passed through the slots 34 and over the top of the ornament 33 and down behind the ornament into the inside of the bag 30. The adjacent faces of the end 30^{aa} and the side wall 30^a are securely attached together by means of stitches 35. A means is provided for holding the mouth opening of the bag in its closed position.

A "Zipper" 36 having a control slide 37 associated therewith is attached to the sides of the mouth opening of the pocket bag 30 and the control slide 37 is adapted to be moved along the length thereof for opening and closing the bag in the usual manner.

In Fig. 15 a belt 41 is strapped around bag 40. The head and tail ornaments 42 are secured to this belt which is removably held on the bag 40.

My invention relates to improvements of pocketbooks made in all sorts of decorative manners in the form of ornamental faces of animals 35 made in all sorts of suitable materials which I have described in my application.

While I have illustrated and described the preferred embodiments of my invention, it is to be understood that I do not limit myself to the precise constructions herein disclosed and the right is reserved to modifications in my new invention to use the same idea in the form of one solid piece chopped by dyes which is similar to the sketches, including materials for ornaments such as wood, glass, Bakelite, plastic rubber, shell, Celluloid and metals, also to all changes and modifications coming within the scope of the invention as defined in the appended claims.

Having thus described my invention, what I claim as new, and desire to secure by United States Letters Patent is:

1. A heads and tails ornament for pocketbooks comprising a pair of hingedly connected frame sections for engagement on the mouth opening of a pocketbook, each frame section having side portions of channel shape in cross section with the arms thereof adapted to be clamped upon the edges of the pocketbook proper, a strip slidably mounted in one side portion and having a projecting portion by which it may be moved, an ornament body for the outer side of said side portion and having headed studs engaging through alignable bayonet openings in said strip and said side portion, and means for holding said strip in positions in which said bayonet slots are in or out of line for holding and releasing said headed studs.

2. A head and tail ornament for pocketbooks comprising a pair of hingedly connected frame sections for engagement on the mouth opening of a pocketbook, each frame section having side portions of channel shape in cross section with the arms thereof adapted to be clamped upon the edges of the pocketbook proper, a strip slid-

ably mounted in one side portion and having a projecting portion by which it may be moved, an ornament body for the outer side of said side portion and having headed studs engaging through alignable bayonet openings in said strip and said side portion, and means for holding said strip in positions in which said bayonet slots are in or out of line for holding and releasing said headed studs, said frame sections having the bottom ends of their side portions pivotally connected together so that the top portions of said frame sections may be moved apart when it is desired to open said pocketbook.

3. A head and tail ornament for pocketbooks, comprising a pair of hingedly connected frame sections for engagement on the mouth opening of a pocketbook, each frame section having side portions of channel shape in cross section with the arms thereof adapted to be clamped upon the edges of the pocketbook proper, a strip slidably mounted in one side portion and having a projecting portion by which it may be moved, an ornament body for the outer side of said side portion and having headed studs engaging through alignable bayonet openings in said strip and said side portion, and means for holding said strip in positions in which said bayonet slots are in or out of line for holding and releasing said headed studs, means on said frame sections for holding said pocketbook in its closed position.

4. A head and tail ornament for pocketbooks, comprising a pair of hingedly connected frame sections for engagement on the mouth opening of a pocketbook, each frame section having side portions of channel shape in cross section with the arms thereof adapted to be clamped upon the edges of the pocketbook proper, a strip slidably mounted in one side portion and having a projecting portion by which it may be moved, an ornament body for the outer side of said side portion and having headed studs engaging through alignable bayonet openings in said strip and said side portion, and means for holding said strip in positions in which said bayonet slots are in or out of line for holding and releasing said headed studs, said projecting portion of said strip extending through an opening formed in said frame section at the top of said side portion, and said projecting portion being adapted to be moved outwards for aligning the enlarged ends of said bayonet openings so that said headed studs may be passed therethrough when it is desired to remove or place said ornament body on said side portion.

5. A head and tail ornament for pocketbooks, comprising a pair of hingedly connected frame sections for engagement on the mouth opening of a pocketbook, each frame section having side portions of channel shape in cross section with the arms thereof adapted to be clamped upon the edges of the pocketbooks proper, a strip slidably mounted in one side portion and having a projecting portion by which it may be moved, an ornament body for the outer side of said side portion and having headed studs engaging through alignable bayonet openings in said strip and said side portion, and means for holding said

strip in positions in which said bayonet slots are in or out of line for holding and releasing said headed studs, said means for holding said strip comprising an inwardly extending projection formed on the bottom of said strip and selectively engageable with complementary recesses formed in the adjacent face of said side portion for restricting the movement of said slide to positions in which said bayonet slots will be either in line or out of line.

6. A head and tail ornament for pocketbooks, comprising a pair of hingedly connected frame sections for engagement on the mouth opening of a pocketbook, each frame section having side portions of channel shape in cross section with the arms thereof adapted to be clamped upon the edges of the pocketbook proper, a strip slidably mounted in one side portion and having a projecting portion by which it may be moved, an ornament body for the outer side of said side portion and having headed studs engaging through alignable bayonet openings in said strip and said side portion, and means for holding said strip in positions in which said bayonet slots are in or out of line for holding and releasing said headed studs, means for holding said strip in position within said side portion, comprising a pin extending inwards from said side portion and engageable through an elongated slot formed in said strip intermediate of its ends.

7. A head and tail ornament for pocketbooks, comprising a pair of hingedly connected frame sections for engagement on the mouth opening of a pocketbook, each frame section having side portions of channel shape in cross section with the arms thereof adapted to be clamped upon edges of the pocketbook proper, a strip slidably mounted in each side portion and having a projecting portion by which it may be moved, an ornament body for the outer side of each side portion and having headed studs engaging through alignable bayonet openings in said strips and side portions, and means for holding said strips in positions in which said bayonet slots are in or out of line for holding and releasing said headed studs.

8. A head and tail ornament for pocketbooks, comprising a pair of hingedly connected frame sections for engagement on the mouth opening of a pocketbook, each frame section having side portions of channel shape in cross section with the arms thereof adapted to be clamped upon edges of the pocketbook proper, a strip slidably mounted in each side portion and having a projecting portion by which it may be moved, an ornament body for the outer side of each side portion and having headed studs engaging through alignable bayonet openings in said strips and side portions, and means for holding said strips in positions in which said bayonet slots are in or out of line for holding and releasing said headed studs, said ornament body for one side of said pocket bag comprising a head and the ornament body for the other side of said pocketbook comprising a tail.

JOSEPH RUBENSTEIN.
